LIGHTING FIXTURE SUPPORT

Filed Dec. 18, 1920

INVENTOR
Benjamin Schaefer
BY
William S. Gluck
ATTORNEY

UNITED STATES PATENT OFFICE.

BENJAMIN SCHAEFER, OF JAMAICA, NEW YORK.

LIGHTING-FIXTURE SUPPORT.

Application filed December 18, 1920. Serial No. 431,705.

To all whom it may concern:

Be it known that I, BENJAMIN SCHAEFER, a citizen of the United States, and a resident of Jamaica, Long Island, in the State of New York, have invented certain new and useful Improvements in Lighting-Fixture Supports, of which the following is a specification.

This invention relates generally to a supporting structure and more particularly to an arrangement for attaching or securing a lighting fixture to a supporting element or surface, and has special reference to improvements in means for attaching or securing an electric fixture in position.

Among the more important difficulties generally encountered in such constructions are: the use of a complex construction which must be assembled and fitted in putting the fixture in place, resulting in an increase of cost of materials as well as labor in the installation of the fixture; inequalities in the element or the surface from which the fixture is to be carried or to which it is to be attached, necessitating the use of tools, and the expenditure of time and labor; the lack of variability in the means for supporting the fixture, to accommodate variations in the fixture or in the surface or element from which the fixture is to be carried; and the necessity of using a number of alternative forms of supports dependent upon the character of the supporting element or surface to which it is to be attached.

The principal objects of my invention are: the provision of a support for a lighting fixture which is of universal application, regardless of whether outlet boxes are used or not or whether the surface or element to which the support is to be secured is the wall itself, a pipe projecting therefrom, a countersunk portion therein or a structure supported from the floor; the provision of a support which is universally variable within reasonable limits to accommodate variations in the dimensions of the fixture; the provision of supporting means, portions of which are relatively variable so as to accommodate any angular variations between the supporting surface and the fixture; the provision of a supporting means for a fixture which is variable to accommodate variations in the extent of the outward projection from the supporting surface of the supporting element, such as the gas pipe or the threaded part extending from the outlet box

or fixture stud attached thereto; the provision of a supporting means for a fixture which renders unnecessary the use of hickies, crow's feet, saddles and similar contrivance; the provision of an improved insulating arrangement; the provision generally of a simpler, less expensive and more efficient lighting fixture supporting arrangement and construction, and one wherein the number of parts and the initial cost is materially reduced and whereby the amount of time and labor necessary for its installation is extremely little, and one which, because of the universality of its application, reduces the number of kinds of brackets that must be kept in stock.

In attaining the foregoing objects and certain additional advantages that will either appear or be pointed out below, I have provided a construction, one embodiment of which is illustrated in the accompanying drawings in which—

Figure 1, is a side view of the lighting fixture in position shown partly broken away to bring to view my supporting means;

Figure 2 is a perspective view of the supporting means removed from its position of support of Figure 1;

Figure 3 is an end view of a detail;

Figure 4 is a view of a fragment of the support showing an alternative manner of securing the support in position.

Figure 5 shows a fragmentary section on line 5—5 of Figure 2;

Figure 6 is a detail sectional view; and

Figure 7 shows a modified embodiment of a detail illustrating a use to which my support can be put.

As will be obvious upon a reading of the specification, the embodiment of the invention illustrated in this application can be used equally well whether the fixture is supported from a side wall or from the ceiling, or even from any other character of supporting surface such as a floor supported base. When therefore the terms "wall" and "surface" are used in the specification and claims, it is to be clearly understood that they are used merely for the purposes of convenience and in the generic sense to indicate all the characters of supports to which the fixture could be attached.

For the purpose of showing a manner of using my invention, I have illustrated in Figure 1, a fixture generally indicated by the reference character 10, and illustrated

as comprising the canopy 12, extension tube 13 and electric socket 14 pendants carried from said tube 13, in any desired or preferred manner. I want it to be clearly understood that this fixture, which in the drawing is shown for the sake of convenience as a wall fixture attached to the wall A and provided with a pendant socket, may take any desired form other than that shown, such as for instance, a form adapted to be suspended from the ceiling. By the use of my invention now to be described, this fixture 10 is attached to or supported from a surface or wall such as A without the mutilation thereof by the use of nails, screws or other affixing means.

The fixture 10 is secured in position by a supporting structure or bracket clearly shown in Figure 2, and comprising generally two relatively adjustable members 15 and 16, one of which is intended to serve as a mounting frame to be supported from or be secured to the wall or surface A and the other of which is intended to serve as an assembly member and to abut against and engage the fixture 10.

The mounting frame or member 15 is preferably though not necessarily made of a stamping of any desired metal and of any desired or required dimensions. In the embodiment illustrated this member 15 comprises generally the two flanges 17 and 18, connected by the web member 19. The flange 17 is given any desired conformation, that shown in the drawing being merely for purposes of illustration. The flange 17 of the member 15 is provided with the opening 21 preferably threaded and preferably dimensioned so as to receive the threaded pipe 40 which extends from the standard outlet box in general use. This opening 21 is aligned with the opening 20 in the flange 18 for the reasons that will be obvious. The member 16 is secured to the member 15 for adjustment relatively thereto, this result being attained preferably by making the member 16 in the form of a threaded rod, received in the threaded opening 20 formed in the flange 18.

The web or connecting portion 19 may take any desired form and in the embodiment illustrated comprises the portions 22 and 23 substantially parallel to the length of the bracket, these portions being connected by the angularly arranged portion 24. As a result of this arrangement the web or connecting portion 19 is arranged to the side of and out of line with the path of movement of the screw rod 16, as well as out of the path of the wiring B as clearly shown in Figure 1. This result could be attained without arranging the part 24 angularly to parts 22 and 23 as illustrated.

The rod 16 is preferably although not necessarily threaded for its full length as

shown, and receives on its outer end the threaded button or head 26 arranged to be brought into abutting relation to the fixture 10. For this purpose the button or head 26 is reduced in diameter at 27 to snugly receive the tubular extension 13, the widened portion 28 forming the stop shoulder 29 which forms a limiting stop for the relative movement of the tube 13 and the button or head 26. This button 26 is preferably made of brass and its outer contour 30 is curved as shown so as to form a harmonious design with the rest of the fixture.

In the use of the support in connection with an outlet box having a threaded part extending therefrom such as shown at C on Figure 1, the members 15 and 16 are first secured in threaded relation as shown in Figure 2. The bracket or supporting unit 15 and 16 is then secured in position on the pipe C by the interengagement of the threads on the pipe C and the opening 21. This same operation will of course hold true, when the element C is a gas pipe or other similar member.

The unitary fixture, comprising the members 12, 13 and 14 is then slipped over the unit bracket 15, 16 as shown in Figure 1, the threaded rod 16 having been positioned with reference to the member 15, so as to have its outer end project beyond the open outer end of the extension tube 13. The button or head 26 is threaded on the end of the rod 16, and, as is obvious, as soon as this button 26 is fully threaded on the rod 16, the continued rotation of the button will cause the rod to rotate therewith, the member 15 of the bracket being held against rotation by the fact that the threads on the pipe C are of such a character that the tendency of the member 15 to rotate with 16 will merely cause the screw threaded connection between the member 15 and the pipe 16 to be still further tightened. The rod 16 as it is rotated with the button 26, will therefore be moved longitudinally inwardly, due to the screw threaded connection between the members 15 and 16, and the fixture 10 will thus be moved into position against the wall or surface A.

The support or bracket thus far described is an extremely simple and inexpensive one, the parts being stock parts and few in number, readily assembled and secured in position without tools and without the loss of time. Furthermore it possesses the added advantage that should the pipe C come out of the outlet box at an angle, as is frequently the case, the flange 17 can be secured thereto in its angular position, and by then bending the web or connecting portion 19 of the member 15 at any point such as that indicated by the arrow in Figure 2, the part 23 and the threaded rod 16 can be positioned so that the fixture will be properly positioned against the wall or support.

ing surface. A still further advantage of my arrangement, is that the members 15 and 16 are universally adjustable, that is regardless of the length of the pipe C or of the fixture 10, there will be no necessity for cutting off a portion of the rod 16 or of the piping or for using an extension coupling as would be the case otherwise. This result is obviously secured by the tele-
10 scoping arrangement secured between the members 15 and 16. As a result of my arrangement also, the universal adjustment will exist even where the outlet box is countersunk in the wall, thus doing away with
15 the necessity for extension pipings or couplings. Where these outlet boxes are not used, I have made my invention equally applicable and equally valuable by providing a supporting or attaching means which can
20 be used under the circumstances, and for this purpose I have provided the flange 17 with such means, which in the embodiment illustrated, take the form of one or more openings 33, screw threaded if desired, to
25 receive either nails or screws 34 whereby the support is secured in position.

In Figure 7 I have illustrated a suggested embodiment in which my supporting means are carried from the ceiling, and in which
30 the button or head 26' is provided with the hook 38 from which a lighting fixture or dome may be carried or by which it may be supported.

Insulation of the supporting structure of
35 my invention is attained by making the flange 17 more or less of insulating material. In the embodiment illustrated, I have provided an insulating bushing 40 externally threaded at 42 for its attachment
40 in the opening 21, and internally threaded at 41 for attachment to the pipe or part C. The bushing is provided with the flange 43, the function of which is obvious from Figure 1. The bushing 40 can be secured in
45 its position on the pipe C by any desired means such as a lock nut (not shown).

Having thus described my invention and illustrated its use, what I claim as new and desire to secure by Letters Patent, is the
50 following:

1. An electric lamp fixture having a mounting frame adapted to be secured to a wall, a canopy like base or shell enclosing the said frame and bearing upon the wall, a tubular extension mounted in the outer end of the shell in line with the axis thereof and open at its outer end to its full diameter, an end body closure sufficiently large in diameter to fit the open outer end of the said end body, and assembly means having the said closure mounted on its outer end and having its inner end threaded to be screwed into said mounting frame whereby the shell is clamped against the wall and the said closure held in place over the outer end of the end body, said mounting frame including a member having a connecting web and two spaced flanges bent therefrom in the same direction and into substantial parallelism. 60
65

2. An electric lamp fixture having a mounting frame comprising a sheet metal member having a connecting web and two spaced flanges bent therefrom in the same direction and into substantial parallelism 70 and adapted to be secured to a wall, a canopy like base or shell enclosing the said frame and bearing upon the wall and having its outer end open, and a closure for said open end, and a threaded rod in threaded engagement with said closure and with one of the flanges of said mounting frame for maintaining said parts in assembled condition. 75
80

3. An electric lamp fixture having a mounting frame comprising a sheet metal member having a connecting web and two spaced flanges bent therefrom in the same direction and into substantial parallelism 85 and adapted to be secured to a wall, a threaded rod in threaded engagement with one of the flanges of said mounting frame, and a nut threaded on the end of said rod whereby a canopy engaged between the wall and the nut will be maintained in adjusted 90
95 position.

In testimony whereof, I have hereunto signed my name.

BENJAMIN SCHAEFER.
